(57) **CLAIM**

(21) Appl. No.: **29/323,925**

The ornamental design for a housing of damper mechanism for ink jet printer, as shown and described.

(22) Filed: **Sep. 3, 2008**

DESCRIPTION

(30) **Foreign Application Priority Data**

Mar. 6, 2008 (JP) 2008-005545

FIG. 1 is a top and right front perspective view of a housing of damper mechanism for ink jet printer, showing my design;

(51) **LOC (9) Cl.** 18-02

FIG. 2 is a front elevational view thereof;

(52) **U.S. Cl.** D18/56

FIG. 3 is a rear elevational view thereof;

(58) **Field of Classification Search** D18/40,
D18/43, 56; 347/47, 86-87

FIG. 4 is a top view thereof;

See application file for complete search history.

FIG. 5 is a bottom view thereof;

(56) **References Cited**

FIG. 6 is a right side elevational view thereof;

U.S. PATENT DOCUMENTS

FIG. 7 is a left side elevational view thereof; and,

6,984,031 B2 * 1/2006 Bailey et al. 347/86
